Primary Examiner — Jack Reickel*Assistant Examiner* — Salamah Jordan(74) *Attorney, Agent, or Firm* — LADAS & PARRY LLP(57) **CLAIM**

The ornamental design for a manual exercise apparatus, as shown and described.

DESCRIPTION

FIG. 1 is a perspective view of a manual exercise device showing the new design;

FIG. 2 is a front elevation view thereof;

FIG. 3 is rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings are for illustration purposes only and form no part of the claimed design.
